Louis T. Lapaugh and
Daniel T. Lapaugh INVENTORS.
By Smith & Denison
this 12th day of August,

UNITED STATES PATENT OFFICE.

DANIEL F. LAPAUGH AND LOUIS T. LAPAUGH, OF UTICA, NEW YORK.

CAR-HEATING APPARATUS.

SPECIFICATION forming part of Letters Patent No. 434,022, dated August 12, 1890.

Application filed May 18, 1889. Serial No. 310,575. (No model.)

To all whom it may concern:

Be it known that we, DANIEL F. LAPAUGH and LOUIS T. LAPAUGH, of Utica, county of Oneida, in the State of New York, citizens of

5 the United States, have invented certain new and useful Improvements in Car-Heating Apparatus, of which the following is a specification, reference being had to the accompanying drawings, in which—

10 Figure 1 is a plan view of the bottom of the car inside. Fig. 2 is a perspective of the interior of the car-body. Fig. 3 is a like view looking into the end. Fig. 4 is an enlarged front elevation of the heater detached. Fig. 15 5 is a side elevation of the same.

This invention relates to devices and mechanisms for heating railway-cars with hot air, the apparatus being independent of the locomotive, so that it will heat a train when the 20 locomotive is detached.

The object of our invention is to produce a means for heating railway-cars with hot air, which will heat the largest quantity of air with a minimum quantity of fuel, and which 25 will be safe in case of a wreck and not liable to burn up, the fire being inclosed beyond all probable chance of escape.

Our invention consists in the several novel features of construction and operation hereinafter described, and which are specifically set forth in the claim annexed.

At a suitable point within the car A, preferably central, we mount or set up our heater B. This heater consists of an outer shell comprising the combustion-chamber, a grate adjacent to the bottom, and a chute or chutes 2, opening into the fire-pot contiguous to the grate.

30 C C represent the pipes for heating air, wound sinuously upward and around the heater B, and thence downward to substan-

tially the bottom of the heater, where the lower end of each heating-pipe is connected to tubing 4, which carries the heated air from the heater to the cars.

45 The floor of the car for a part of its distance or width is provided with an air-chamber 5 below the bottom proper, and 6 is a port at each end of the car for admitting fresh air into this chamber, and each port is provided 50 with a slide or other damper for closing the same wholly or partially. The lower ends of the heating-pipes C open into this chamber 5, as shown at 7, and receive fresh air from this chamber. A portion of the bottom of this car 55 is also elevated and covered with a removable grating 8, by the removal of which the pipes 4 can readily be reached, examined, or repaired, if necessary.

At 9 we show coal-bunkers for the storage 60 of fuel.

What we claim is—

A car-heating apparatus consisting of a car constructed of iron and provided with an air-chamber 5, and means for admitting air 65 thereto, and a piping-slot covered with a removable grating, a heater mounted in said car, consisting of a body provided with a grate and air-heating pipes having one end connected to the air-chamber 5, and thence wound 70 upward and sinuously around the body to its top, and thence downward to the discharge-pipe, to which it is connected, and discharge-pipes leading from the heater to the other cars of the train, substantially as described.

75 In witness whereof we have hereunto set our hands this 11th day of May, 1889.

DANIEL F. LAPAUGH.

LOUIS T. LAPAUGH.

In presence of—

H. P. DENISON,

FRANK C. CROWELL.
